(57) **CLAIM**

The ornamental design for a handle for a skin cleansing device, substantially as shown and described.

DESCRIPTION

FIG. 1 is a bottom, front and left side perspective view of our new design for a handle for a skin cleansing device;

FIG. 2 is a right side elevation view of the handle of FIG. 1;

FIG. 3 is a front elevation view of the handle of FIG. 1;

FIG. 4 is a left side elevation view of the handle of FIG. 1;

FIG. 5 is a rear elevation view of the handle of FIG. 1;

FIG. 6 is a top plan view of the handle of FIG. 1; and,

FIG. 7 is a bottom plan view of the handle of FIG. 1.

The broken lines showing an on-off button form no part of the claimed design.

1 Claim, 4 Drawing Sheets
